UNITED STATES PATENT OFFICE.

GEORGE ALFRED SQUIRE, OF BAYONNE, NEW JERSEY.

DESIGN FOR THE ORNAMENTATION OF A SEWING-MACHINE.

SPECIFICATION forming part of Design No. 15,217, dated August 5, 1884.

Application filed May 31, 1884. Term of patent 14 years.

To all whom it may concern:

Be it known that I, GEORGE ALFRED SQUIRE, a citizen of the United States, residing at Bayonne, in the county of Hudson and State of New Jersey, have invented and produced a new and original Design for the Ornamentation of Sewing Machines, of which the following is a specification.

In the accompanying illustrations, Figures 1 and 2 are opposite views, in perspective, of a sewing-machine plate and arm ornamented with my new designs. Figs. 3 and 3^a (one of which is a reversal or negative of the other) show the ornaments for the sides of the front end of the cloth-plate. Figs. 4 and 4^a (one of which is a negative of the other) are the ornaments for the center of the sides of the cloth-plate; Figs. 5 and 6, the ornaments for the opposite sides of the rear end of the same, and Fig. 7 the ornament for the center thereof. Figs. 8 and 9 show the main ornaments for the opposite sides of the arm; Figs. 10, 11, 12, and 13, the ornaments for the post of the arm; Figs. 14 and 14^a, the ornaments for the opposite sides of the forward part of the arm; and Figs. 15, 16, and 16^a, the ornaments for the upper side of the arm.

My new ornaments have a common resemblance to each other, and are composed of branches, sprays, or groups of leaves, stems, buds, and flowers, much like those of the common daisy.

Group A, which is to ornament the sides of the front end of the cloth-plate, comprises three open flowers, six buds, and three main curved stems.

Group B, which is for the center of the sides of the cloth-plate, has two main diverging stems and four buds and three open flowers.

Group C, which is for the rear side of the back end of the cloth-plate, is slightly larger than group A, and has several curved stems, three open flowers, and seven buds.

Group D, which is for the front side of the rear end of the cloth-plate, comprises one main stem and several smaller ones, three open flowers, and four buds.

Group E, which is for the center of the cloth-plate, has drooping or outwardly-curved stems, three open flowers, and numerous buds.

Group F is the main ornament for the front

side of the arm, and comprises three open flowers, six buds, and a long stem, the slender forward end of which extends into the last three letters of a word—in this case the word "Singer"—placed at the front part of the group. 55

Group G is the main ornament for the rear side of the arm, and has three open flowers, six buds, and several slender branches or stems, the longest of which extends into a word—in this case the word "Singer"—placed at the forward part of the group. 60

Group H ornaments the front side of the post of the arm, and has two diverging branches, each bearing an open flower and two buds. 65

Group I ornaments the rear side of the post of the arm, and has three open flowers and drooping branches.

Group J ornaments the face-plate, and has three open flowers, with buds above and below the same, and a small drooping branch near its base. 70

Group K is for the inner side of the post of the arm, and has only a single flower with 75 stems and leaves.

Group L ornaments the opposite sides of the front end of the arm, and has a single open flower and one bud.

Group M consists of words in German-text letters placed on the upper side of the arm between two small groups, N, each having a single flower with leaves and stems. 80

I claim—

1. The design for the ornamentation of sewing-machines, consisting of group A, substantially as shown. 85

2. The design for the ornamentation of sewing-machines, consisting of group B, substantially as shown. 90

3. The design for the ornamentation of sewing-machines, consisting of group C, substantially as shown.

4. The design for the ornamentation of sewing-machines, consisting of group D, substantially as shown. 95

5. The design for the ornamentation of sewing-machines, consisting of group E, substantially as shown.

6. The design for the ornamentation of sewing-machines, consisting of group F, substantially as shown. 100

(over)

7. The design for the ornamentation of sewing-machines, consisting of group G, substantially as shown. 3
8. The design for the ornamentation of sewing-machines, consisting of group H, substantially as shown. 5
9. The design for the ornamentation of sewing-machines, consisting of group I, substantially as shown. 7
10. The design for the ornamentation of sewing-machines, consisting of group J, substantially as shown. 10
11. The design for the ornamentation of sewing-machines, consisting of group K, substantially as shown. 15
12. The design for the ornamentation of sewing-machines, consisting of group L, substantially as shown. 17
13. The design for the ornamentation of sewing-machines, consisting of group M, substantially as shown. 20
14. The design for the ornamentation of sewing-machines, consisting of the combination of groups A, B, C, D, and E, substantially as shown. 25
15. The design for the ornamentation of sewing-machines, consisting of the combination of groups F, H, and L, substantially as shown. 30
16. The design for the ornamentation of sewing-machines, consisting of the combination of groups G, I, and L, substantially as shown. 33
17. The design for the ornamentation of sewing-machines, consisting of the combination of groups F, G, H, I, J, K, L, and N, substantially as shown. 35
18. The design for the ornamentation of sewing-machines, consisting of the combination of groups A, B, C, D, E, F, G, H, I, J, K, L, and N, substantially as shown. 39

In testimony whereof I affix my signature in the presence of two witnesses.

GEORGE ALFRED SQUIRE.

Witnesses:

L. B. MILLER,
A. D. HARTWELL.
